The ornamental design for an arm for use in a compacting mechanism for use with a refuse container, as shown and described.

DESCRIPTION

FIG. 1 is a perspective view of an arm for use in a compacting mechanism for use with a refuse container showing my new design;

FIG. 2 is a front elevational view of the arm for use in a compacting mechanism for use with a refuse container of FIG. 1;

FIG. 3 is a rear elevational view of the arm for use in a compacting mechanism for use with a refuse container of FIGS. 1 and 2;

FIG. 4 is a left side elevational view of the arm for use in a compacting mechanism for use with a refuse container of FIGS. 1 to 3, the ride side elevational view being a mirror image thereof;

FIG. 5 is a top plan view of the arm for use in a compacting mechanism for use with a refuse container of FIGS. 1 to 4; and,

FIG. 6 is a bottom plan view of the arm for use in a compacting mechanism for use with a refuse container of FIGS. 1 to 5.
